UNITED STATES PATENT OFFICE.

FRED D. CHAMBERS, OF WASHINGTON, DISTRICT OF COLUMBIA, ASSIGNOR OF ONE-FOURTH TO FRANK E. BEATTY, OF WASHINGTON, DISTRICT OF COLUMBIA.

ROTARY TOOL.

SPECIFICATION forming part of Letters Patent No. 691,596, dated January 21, 1902.

Application filed October 9, 1901. Serial No. 78,113. (No model.)

To all whom it may concern:

Be it known that I, FRED D. CHAMBERS, a citizen of the United States, residing at Washington, in the District of Columbia, have invented certain new and useful Improvements in Rotary Tools, of which the following is a description, reference being had to the accompanying drawings and to the figures of reference marked thereon.

10 My invention relates to rotary cutting-tools, such as those used for milling, boring, drilling, cutting, burnishing, and the like.

It is the object of my invention to provide simple and efficient means by which such tools may be detachably secured to the arbors by which they are carried; and with this object in view my invention consists in the tool hereinafter described and claimed and the means described and claimed by which it is

20 secured to its arbor.

In the drawings, Figure 1 is a longitudinal view, partly in elevation and partly in section, showing the tool secured to the arbor. Fig. 2 is a horizontal sectional view taken on line 2 2 of Fig. 1. Fig. 3 is a detail view. Fig. 4 is a longitudinal view similar to Fig. 1, but showing a modification. Fig. 5 is a top plan view of the tool shown in Fig. 4, and Fig. 6 is a detail view.

30 In the milling-machines commonly used the milling tool or head is secured to its arbor by screw-threading it onto the arbor. The resistance of the work causes the tool to be driven onto the arbor so firmly that it is a matter of great difficulty to unscrew it and often it cannot be unscrewed without injury to the tool. I have in an application for Letters Patent filed on the 19th of June, 1901, Serial No. 65,183, shown a construction in

35 which this difficulty is obviated as well as other difficulties found to arise where milling tools or heads are secured to their arbors by screw-threads or where they are held from rotation on their arbors by keys.

40 The present invention is an improvement upon the invention of my application referred to.

45 Describing my invention in detail, 1 is the arbor or spindle by which the milling or other tool is carried and by which it is rotated.

This arbor or spindle has at its end a non-circular portion 2, as in the invention of my application above referred to. This non-cylindrical portion is preferably polygonal in cross-section. I have shown it hexagonal in cross-section, as it should be in cross-section either a hexagon or some regular polygon in which the angles between adjacent sides are greater than a right angle for reasons which will be hereinafter explained.

55 Above the non-circular portion 2 the arbor is circular in cross-section, as shown at 3, and of greater diameter than the diameter of the non-circular portion. This portion 3 may be tapered, as shown in Fig. 1, or cylindrical, 65 as shown in Fig. 4. Above this portion of the arbor and of greater diameter than the portion 3 is a screw-threaded portion 4.

60 On the portion 3 of the arbor is fitted a sleeve 5, which is shown tapered in Fig. 1 to fit the tapered portion 3, as there shown, and is shown cylindrical in Fig. 4 to fit the cylindrical portion 3, as there shown. This sleeve 5 is provided with an outwardly-turned flange 6 at its upper end and an interrupted flange 7 at its lower end, which may be outwardly turned, as shown in Figs. 1, 2, and 3, or inwardly turned, as shown in Figs. 4 and 6. Whether outwardly turned or inwardly turned it is cut away at intervals, the cut-away portions preferably equal in length to the portions which remain. The outwardly-turned flange 6 at the upper end of the sleeve 5 is engaged by an inwardly-turned flange 8 at the lower end of a sleeve 9, which is internally screw-threaded to fit the screw-threaded portion 4 of the arbor. This sleeve 9 is preferably provided with means, such as notches 10, by which it may be engaged by a spanner.

70 In the form shown in Figs. 1, 2, and 3 the lower end of the sleeve 5 is adapted to engage an inwardly-turned flange 11 on the tool 12, the flange 11 being cut away, as shown, to permit the portions of the flange 7 to enter

75 between the remaining portions of the flange. 80 The tool 12, as shown in Figs. 1, 2, and 3, is formed to engage the non-cylindrical portion of the arbor and is also adapted to receive the lower end of the sleeve 5.

85 In securing the tool to the arbor in the con-

100

struction shown in Figs. 1, 2, and 3 the tool is first slipped upon the non-cylindrical portion of the arbor. The sleeve 5 is then brought down, and the portions of its flange 7 which are 5 not cut away enter between the portions of the flange 11, and by turning the sleeve 5 these portions of the flange 7 engage beneath the portions of the flange 11. A lug 13 on the sleeve 7 is arranged to engage the end of one 10 of the portions of the flange 11 and prevent its being rotated beyond the point at which the portions of the flanges 7 and 11 are in full engagement. The tool being thus engaged, the sleeve 9 is rotated to draw the sleeve 5 15 upward upon the tapered portion 3 and to hold the tool firmly upon the arbor. In order to release the tool, a slight backward turn of the sleeve 9 permits the sleeve 5 to be turned to release its flange 7 from engagement with 20 the flange 11 of the tool.

In forming the flange 11 of the tool I preferably avoid all right angles by rounding the ends of the cut-away portions and rounding the recess below the flange, as shown. By 25 thus avoiding angles the liability of injury to the tool in tempering is avoided.

In the construction shown in Figs. 4, 5, and 6 I have shown the sleeve 5 provided with inwardly-turned flange 7 and the tool 12 is 30 shown with outwardly-turned flange 11. This necessitates providing the tool with a more or less extensive shank. The operation of securing the tool to the arbor in this form of my invention is substantially the same as 35 above described. In these figures of the drawings I have also shown the portion 3 of the arbor and the sleeve 5 as cylindrical instead of tapering, as in Fig. 1. It will be understood that the tapered form may be used 40 with sleeves having inturned lower flanges to fit tools having shanks, as shown in Figs. 4 and 5, and that the cylindrical form may be used with sleeves having outwardly-turned lower flanges, as shown in Figs. 2 and 3. In 45 fact, it is desirable and I contemplate providing each arbor, whether tapered or cylindrical, with two sleeves, one with inturned lower flange and the other with outwardly-turned lower flange, and to use either of them 50 as may be required, the two being interchangeable and the same upper sleeve 9 being used with both.

Having thus described my invention, what I claim, and desire to secure by Letters Patent, is—

1. A rotary tool, having a central bore adapted to fit the non-circular end of an arbor and provided with an interrupted flange in combination with an arbor, a sleeve carried by 55 the arbor, having at its lower end an inter-

rupted flange adapted to engage the flange of the tool and means for securing the sleeve to the arbor; substantially as described.

2. A rotary tool, having a central bore adapted to fit the non-circular end of an arbor and 65 provided with an interrupted flange in combination with an arbor formed in the rear face of the tool, a sleeve carried by the arbor having at its lower end an outwardly-turned interrupted flange adapted to engage the flange 70 of the tool and means for securing the sleeve to the arbor; substantially as described.

3. A rotary tool having a central bore adapted to fit the non-circular end of an arbor and 75 provided with an interrupted flange, in combination with an arbor, a sleeve carried by the arbor having at its lower end an interrupted flange adapted to engage the flange of the tool, a stop carried by the sleeve and means for securing the sleeve to the arbor; 80 substantially as described.

4. A rotary tool having a central bore adapted to fit the non-circular end of an arbor and provided with an interrupted flange, in combination with an arbor having a tapered portion 85 above its non-circular end, a tapered sleeve carried by the arbor having at its lower end an interrupted flange adapted to engage the flange of the tool, and means for securing the sleeve to the arbor; substantially as described.

5. A rotary tool having a central bore adapted to fit the non-circular end of an arbor, and provided with an interrupted flange in combination with an arbor, a sleeve carried by 95 the arbor having at its lower end an interrupted flange adapted to engage the flange of the tool and having a flange at its upper end, of a second sleeve having a flange adapted to engage the upper flange of the first sleeve and 100 engaging screw-threads on the arbor; substantially as described.

6. A rotary tool having a central bore adapted to fit the non-circular end of an arbor, and provided with an interrupted flange, in combination with an arbor having a tapered portion 105 above the non-circular end, a tapered sleeve carried by the arbor, having at its lower end an interrupted flange adapted to engage the flange of the tool and having a flange at 110 its upper end, of a second sleeve having a flange adapted to engage the upper flange of the first sleeve and engaging screw-threads on the arbor; substantially as described.

In testimony whereof I affix my signature 115 in presence of two witnesses.

FRED D. CHAMBERS.
